(57) **CLAIM**

The ornamental design for a drawer organizer, as shown and described.

DESCRIPTION

FIG. 1 is a front, left, top perspective view of a drawer organizer, showing my new design;

FIG. 2 is a rear, right, bottom perspective view thereof;

FIG. 3 is a rear, right, top perspective view thereof;

FIG. 4 is a front elevational view thereof;

FIG. 5 is a rear elevational view thereof;

FIG. 6 is a left side view thereof;

FIG. 7 is a right side view thereof;

FIG. 8 is a top plan view thereof;

FIG. 9 is a bottom plan view thereof;

FIG. 10 is an enlarged view of detail 10 in FIG. 1;

FIG. 11 is an enlarged view of detail 11 in FIG. 3; and,
FIG. 12 is a front, left, top perspective view of the drawer organizer, indicating the usage environment.

The dashed broken lines in the figures are for the purposes of illustrating portions of the drawer organizer that form no part of the claimed design.

The dash-dot-dash broken lines are for notating enlarged views and form no part of the claimed design.

The dashed broken lines in the FIG. 12 are for the purposes of indicating the usage environment of the drawer organizer and form no part of the claimed design.

1 Claim, 12 Drawing Sheets
